DOG'S BED

John Randolph Madlem, Catskill, N.Y., assignor to
Creative Associates of Albany, Ltd., Latham, N.Y.,
a corporation of New York

Filed Sept. 26, 1966, Ser. No. 4,042

Term of patent 14 years

(Cl. D30—41)

FIGURE 1 is a perspective view of a design for a dog's bed showing one embodiment of my invention.

FIGURE 2 is a top plan view of the dog's bed shown in FIGURE 1.

FIGURE 3 is a perspective view of a dog's bed viewed from the front left showing another embodiment of my invention.

FIGURE 4 is a perspective view of the dog's bed shown in FIGURE 3 viewed from the rear right.

FIGURE 5 is a perspective view of the dog's bed shown in FIGURE 3 viewed from the rear.

FIGURE 6 is a rear elevational view of the dog's bed shown in FIGURE 1.

FIGURE 7 is a front elevational view of the dog's bed shown in FIGURE 1.

FIGURE 8 is a top plan view of the dog's bed shown in FIGURE 3.

The bottom of the dog's bed shown in the drawings is flat.

I claim:

The ornamental design for a dog's bed, substantially as shown and described.
